(57) **CLAIM**

The ornamental design for a breast pump bra button, as shown and described.

DESCRIPTION

FIG. 1 is a front, left side perspective view of a breast pump bra button showing my new design;

FIG. 2 is a front elevational view thereof;

FIG. 3 is a left side elevational view thereof;

FIG. 4 is a top plan view thereof; and,

FIG. 5 is an enlarged view of a portion indicated in FIG. 2. The broken lines in the drawings show portions of the breast pump bra button that form no part of the claimed design. The dash dot lines in FIGS. 2 and 5 are for the purpose of depicting the boundary line of the enlarged view and form no part of the claimed design.
